J. SWAN.

COMB.

APPLICATION FILED APR. 24, 1920.

Patented June 21, 1921.

UNITED STATES PATENT OFFICE.

JUDGE SWAN, OF HAMILTON, ONTARIO, CANADA.

COMB.

1,382,568.

Specification of Letters Patent. Patented June 21, 1921.

Application filed April 24, 1920. Serial No. 376,414.

To all whom it may concern:

Be it known that I, JUDGE SWAN, a citizen of the Dominion of Canada, residing at Hamilton, in the Province of Ontario and 5 Dominion of Canada, have invented a new and useful Comb, of which the following is a specification.

This invention relates to devices especially designed for the treatment of hair, and 10 it is the object of the invention to provide novel means to facilitate the pressing and straightening of the hair preparatory to the waving treatment.

With the foregoing and other objects in 15 view which will appear as the description proceeds, the invention resides in the combination and arrangement of parts and in the details of construction hereinafter described and claimed, it being understood 20 that changes in the precise embodiment of the invention herein disclosed, may be made within the scope of what is claimed, without departing from the spirit of the invention.

Referring to the drawing:—

25 Fig. 1 illustrates a rear elevational view of a device constructed in accordance with the present invention.

Fig. 2 illustrates a front elevational view of the same.

30 Fig. 3 illustrates a side elevational view, and

Fig. 4 illustrates a sectional view taken on line 4—4 of Fig. 1.

Referring to the drawing in detail, the 35 device includes the opposed members 5 and 6 respectively, each of which members includes a handle 7' and jaw section 7, the jaw section of each member extending laterally thereto, and provided with a curved 40 outer edge indicated at 8.

These opposed members 5 and 6 cross each other and are pivotally connected as by means of the pivot pin 9 passing through suitable registering openings formed in the 45 members 5 and 6, there being a stop 10 provided on each section adjacent the pivot point thereof, for contacting with the adjacent section to restrict movement of one section with relation to the other.

50 The jaw sections 7, are relatively wide and flat, so that the same will grasp a number of strands of hair when the same are put to use. Disposed between the jaw sections 7 is a central jaw section 11 which is 55 also relatively wide and flat so that the surfaces thereof will closely engage the jaw sec-

tions 7, and as shown this jaw section 11 is provided with a base 12 which has a portion thereof overlying one of the opposed sections where the same has pivotal connection with the opposed sections through the pivot pin 9.

A coiled spring 13 has one end thereof extending into a suitable opening provided in the base 12, on the respective sides thereof, the opposite ends of the springs 13 being right angled and extending into suitable openings formed in the handle portions of the respective sections 5 and 6.

In view of the foregoing it will be seen 70 that the central jaw section 11 is normally maintained in spaced relation with the jaw sections 7, by means of the coiled springs 13, the coiled springs 13 at the same time acting to hold the jaw sections in spaced relation with each other.

In the operation of the device, the same is positioned over a heating medium, and to this end a thermometer 14, is positioned on the base 12 by means of which a predetermined temperature of the jaws 7 and 11 may be had for the efficient operation of the device.

When the jaws have become heated to the proper degree, the device is positioned in the hair, the handles thereof manipulated to cause the jaws 7 and 11 to grasp strands of hair, whereupon the device is moved through the hair with the result that the hair is pressed and straightened, and freed 90 of all irregularities.

Having thus described the invention, what I claim as new is:—

1. In a device of the character described, opposed sections pivotally connected together, each of said sections including a handle, and a jaw, a central jaw pivotally connected to one of the opposed sections, resilient means connecting the handles and central jaw for normally holding the jaw sections in spaced relation with each other.

2. In a device of the character described, opposed sections pivotally connected together, each of said sections comprising a handle and jaw section, each of the jaw sections including a blade having a curved outer surface, a central jaw section disposed between the first mentioned jaw section, and spring members connecting the central jaw section with the handles.

3. In a device of the character described, opposed sections pivotally connected to-

2
gether, relatively flat jaw sections forming a part of each of the opposed sections, a central pivoted jaw section, and coiled springs connecting the central jaw section with the opposed sections for normally maintaining the jaw sections in spaced relation with each other.

In testimony that I claim the foregoing as my own, I have hereto affixed my signature in the presence of two witnesses.

JUDGE SWAN.

Witnesses:

LENA GOLDBERG,
VIOLET A. MURPHY.
